UNITED STATES PATENT OFFICE.

EDGAR ALLEN WASSON AND FRANCIS MARIAN COOLEY, OF BEAUMONT, TEXAS.

OIL-TANK.

1,128,202.

Specification of Letters Patent.

Patented Feb. 9, 1915.

Application filed October 28, 1913. Serial No. 797,803.

To all whom it may concern:

Be it known that we, EDGAR A. WASSON and FRANCIS M. COOLEY, citizens of the United States, and residents of Beaumont, in the county of Jefferson and State of Texas, have invented a new and useful Improvement in Oil-Tanks, of which the following is a specification.

This invention relates to an improvement in oil tanks, and more particularly to an improved means for extinguishing fires in tanks.

One of the principal objects of the invention is to provide an oil tank with means for allowing the escape of exploded gases, when the gases are ignited by lightning or other sources.

A further object of the invention is to provide an oil tank having outlet valves, and means for causing the explosion of the gases contained within the tank upon lightning striking near the tank, the valves being adapted to open to allow escape of the explosive gases, and then to shut whereby to cut off the supply of air, thus smothering the fire.

Another object of the invention is to provide the top of an oil tank with openings, and automatic closures therefor adapted to be opened by the force of exploding gases to allow the escape of the same, and to subsequently automatically close the openings, for cutting off the supply of oxygen, thereby extinguishing the flames.

Another object of the invention is the provision of a device for extinguishing fires in oil tanks, which will be simple, durable, efficient in operation, and inexpensive in manufacture.

With these and other objects in view the invention resides in the construction, combination, and arrangement of parts, herein-after more fully described and claimed, and illustrated in the accompanying drawing in which like characters of reference indicate like parts throughout the figures, of which,

Figure 1 represents a top plan view of a portion of the roof of an oil tank, constructed according to our invention. Fig. 2 represents a vertical, transverse, sectional view taken on the plane indicated by the broken line 2—2 of Fig. 1, and Fig. 3 represents a detail plan view of one of the closures.

Referring more particularly to the drawing, 5 indicates a circular oil tank provided

with a substantially conical roof 6, having its outer edge bent downwardly and riveted or otherwise secured to the upper edge of the tank. The apex of the roof has secured 60 thereon a hollow cap 7, supporting a ball 8, through which extends a lightning rod 9, the inner end of which projects through an opening 10 in the apex of the roof into the interior of the tank. The roof is provided 65 adjacent cap 7 with a plurality of equidistant substantially triangular shaped openings 11, and at its outer edge with a circular series of equidistant substantially rectangular openings 12, said openings 11 and 70 12 being arranged radially of the roof, the openings 12 extending from the extreme outer edge of the roof to a point inwardly thereof.

All of the roof openings are provided 75 with closures 13 which are of substantially the same shape as the openings but of a slightly larger perimeter, and the closures are hinged as at 14 to the upper side of the roof, the closures for openings 11 being 80 hinged at their outer edges to the roof and the closures for openings 12 being hinged at their inner edges to the roof.

In order to normally hold closures 13 against the roof, pintle pins 15 of the hinges 85 have interposed thereon between the adjacent leaves of the hinges, coiled springs 16 having their opposite ends bent over the hinge leaves for pressing the closures in contact with the roof, to normally close the 90 openings.

By reason of the roof being conical the gases from the oil will collect at first at the apex of the roof, and the pressure will therefore be greatest at this point, and it is for 95 this reason that openings have been provided near the apex, so that as the pressure of the collecting gases overcomes the tension of the springs governing the central closures, said closures will open to allow 100 escapement of the gases, thus forming a continual vent.

The lightning rod is so arranged that upon being struck by lightning, the lightning will be carried into the interior of the 105 tank, and explode the gases therein, which explosion will open closures 13 against the tension of springs 16, as illustrated in dotted lines in Fig. 2, thus allowing the exploded gases to escape, and the force of the explosion having been spent, the closures will 110 automatically resume their normal positions

by means of springs 16, and will thus cut off the supply of air to the interior of the tank, thereby smothering the flames and causing the fire to die out.

5 It is well known that in many instances lightning upon striking a rod and passing through the ground wire, will jump the wire, since the latter is in many instances too small to accommodate the huge amount 10 of electricity, thus greatly damaging the building or other structure to which the rod is secured. Especially is this true, if the structure is made of metal. Should a metallic or a wooden tank cover be provided 15 with a lightning rod having a ground wire, the danger of a bolt of lightning jumping the wire and tearing a hole in the roof would be ever present, and should this occur, it is obvious that the resulting fire 20 would consume the contents of the tank and would consume the roof were the latter composed of inflammable material, unless the opening were immediately closed to exclude the air, which of course would be 25 improbably accomplished. Were the tank not provided with a lightning rod at all, the roof would be torn apart upon a lightning stroke and the same result would ensue. The peculiar arrangement of our 30 lightning rod materially diminishes these dangers by conducting the lightning within the tank so as to cause the explosion in a manner that it can do no harm, since the closures will shut down over the openings 35 subsequent to the explosion and thus cut off all air supply and smother the fire.

Although we have described the preferred embodiment of our invention, we may desire to make such changes in the construction, combination, and arrangement of parts 40 thereof, as do not depart from the spirit of the invention and the scope of the appended claims.

We claim:

45 1. An oil tank having a roof sloping upwardly toward its center and provided with a lightning rod adapted to conduct lightning within the tank at that point and a plurality of openings in proximity to said 50 rod, closures for said openings hinged to said roof at their outer edges and tapering inwardly therefrom, said roof provided with a circular series of openings at its outer edge, closures for last said openings 55 hinged to said roof at their inner edges, and springs for holding all of said closures normally against said roof, for closing said openings.

2. An oil tank having a roof sloping upwardly toward its center and provided with a lightning rod adapted to conduct lightning within the tank, and a plurality of openings in proximity to said rod, closures

for said openings hinged to said roof, said roof provided with a circular series of 65 openings at its outer edge, said openings extending from the outer edge of the roof toward the center thereof, closures for last said openings hinged to said roof, and means for normally holding said closures 70 against said roof, for closing said openings.

3. An oil tank having a roof sloping upwardly toward its center, and provided with a lightning rod adapted to conduct lightning within the tank and with a plurality 75 of openings in proximity thereto, said roof provided with openings at its outer edge, and means for normally closing all of said openings.

4. An oil tank having a roof provided 80 with a lightning rod adapted to conduct lightning within the tank and with a plurality of openings, and closures hinged to said roof and adapted to normally close said openings. 85

5. An oil tank having a roof provided with a lightning rod adapted to conduct lightning within the tank, and a plurality of openings arranged in rings one within the other, one of the rings being in close 90 proximity to said rod, and closures for said openings adapted to normally close the same.

6. An oil tank having a roof sloping upwardly toward its center, and provided 95 with a series of openings at its apex, and a second series of openings at its outer edge, means for normally closing all of the openings and means for conducting lightning within the tank at a point adjacent the 100 openings at the apex of the roof.

7. An oil tank having a roof provided with an opening therein, a hollow cap secured above said opening, a ball supported by said cap, and a lightning rod extending 105 through said ball and into the tank through the opening in the roof.

8. An oil tank having a roof sloping upwardly toward its center and provided with an opening at its apex, a hollow cap secured 110 above said opening, a lightning rod supported by said cap and extending into the tank through the opening in the roof, said roof provided with a series of openings in proximity to the lightning rod, and means 115 for normally closing said openings.

9. An oil tank having a roof provided with openings, check valves for preventing the entrance of air into the tank through the openings and an electrical conductor for 120 conducting lightning within the tank.
